UNITED STATES PATENT OFFICE.

RAYMOND D. SMITH, OF PLEASANTVILLE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

IMITATIVE CANDLE FITTING.

Application filed January 29, 1923. Serial No. 615,711.

This invention relates to a decorative form of electric light fitting made to imitate the appearance of a candle and particularly concerns improvements in the design and mechanical construction of so-called "candle fittings" when they are of the removable type requiring no wiring to install, such as form the subject of my two co-pending applications, Serial No. 534,996, filed February 8, 1922, and Serial No. 543,880, filed March 15, 1922.

Among the objects of the invention are to increase the degree to which such an attachment shall resemble the more expensive and specially designed candle fixtures by concealing more completely the original appearance of the ordinary socket fixture to which my attachment is applied.

The improvements constituting my present invention are also usable to good advantage in the manufacture of so-called socket extensions which are commonly provided with a male threaded plug at one end for mounting in an ordinary electric lamp socket, and with a female threaded receptacle at the other end to receive an ordinary electric lamp bulb, and in any tubular device employing metallic threaded screw shells or like members at one or both of its ends.

A particular provision of the present improvements is a novel means for mounting an inner body structure inside of a tube made of paper or correspondingly soft material, in a secure and simple manner and by a very simple and cheap operation, whether or not such tube and structure are designed for use as electrical fittings.

The invention is more definitely set forth in the following description, which with the accompanying sheet of drawings, gives specifications of a preferred embodiment which is subject, however, to many departures and modifications within the scope of the appended claims.

In the drawings, Fig. 1 is a vertical central section taken lengthwise through the two main parts of my improved candle fitting, the socket to which they are applied and which they largely conceal, when applied, being indicated by dot-dash lines.

Fig. 2 is a perspective view of the body structure that is mounted inside the paper

candle tube, a section of the connecting tubular wall being broken away.

Fig. 3 shows an assembling tool as it engages with the structure of Fig. 2 and with the paper tube to fasten the former securely within the latter.

Fig. 4 is a transverse section taken on the plane 5-5 in Fig. 1 looking down, the prongs on the holding spider being shown in the position they occupy before being pressed outwardly into the paper tube by the tool shown in Fig. 3.

Fig. 5 is a view similar to Fig. 4 after the prongs are set into the walls of the paper tube.

Throughout the different views of the drawings each part is designated by a like symbol.

The parts of my improved fitting comprise the outer paper tube 10, the female screw shell 11, to which the spider 12 is fastened by eyelets 13,—the male screw shell 14 to which is fastened a similar spider 15 by eyelets 16,—a metal tube 17 which spaces the spider 12 from the spider 15 against the pull of the long, center screw 18 whose head clamps the center contact washer 19 and insulating block 20 against the male screw shell 14 and whose threaded end by means of the nut 21 clamps the center contact tongue 22 and insulating washer 23 against the female screw shell 11.

In the original forms of spider, 12 and 15, as shown in Figs. 3 and 4, the prongs 24 are radially retracted by transradial grooves or channels 25 formed adjacent thereto in the spiders, so that the overall diameter of the prongs is slightly smaller than the inside diameter of the paper tube 10. This permits the assembled structure shown in Fig. 2 to be inserted in the tube in desired lengthwise relation. The spiders 12 and 15 may further be ribbed as at 32 to prevent them from collapsing when the channelled portions 25 are flattened as hereinafter described. It will be seen in Figs. 2 and 3 that the two spiders are assembled in rotatively staggered relation so that the pronged portion of one falls axially opposite the space between the pronged portions on the other. This permits a tube-like tool 26 composed of two similar parts hav-

ing inter-engaging castellated ends 27 to encompass the screw shells and fit loosely inside the paper casing 10 and apply longitudinal pressure simultaneously on the channelled portions 25 of both spider 12 and spider 15 whereby these channelled portions are flattened and the prongs 24 forced outwardly into, but preferably not through, the walls of the tube 10. The two parts of the 10 tool 26 then separate and are removable from the assembled structure leaving the spiders securely fastened against rotative or lengthwise movement within the tube. There is thus provided, by a simple and 15 quick operation, a structure having the necessary annular space between male screw shell 14 and candle tube 10 to enable the latter to encompass and conceal the reduced diameter portion of the lamp socket while 20 capable of being screwed into same like an ordinary lamp bulb.

To better the resemblance to a candle with its holder, I provide an open ended sheet metal husk 30 of proper diameter at its 25 small end to slip easily onto the larger diameter portion of the lamp socket and come to rest on the edge of the socket cap. This husk has a slot 31 to accommodate the shank of a switch key or the bell mouth guide for 30 a pull chain and also gives a little spring to the husk which enables it to accommodate very slight variations in the diameter of different sockets it may be required to fit.

The contour, or decorative design, of husk 35 30 is obviously a matter of choice, the point with which this invention is concerned being that it, together with the tube 10, covers up a larger part of the old socket than has heretofore been accomplished by removable attachments for a like purpose and thereby more completely disguises the appearance of the ordinary lamp socket and more completely transforms it in appearance to resemble a candle fixture.

45 The ruggedness and economy of manufacturing resulting from the new features of construction herein described will be apparent and the following claims will be taken to include all equivalent constructions 50 which come within the spirit of the invention.

Claims:

1. A device for securing an electric lamp receptacle shell to the wall of a surrounding 55 tubular support, embodying in combination, a mounting plate fixedly secured in trans-axial relation to one end of said shell and extending outside the circumference of said shell to provide a mounting flange, the said mounting flange being channeled to provide for radial extension when flattened, thereby to effect mounting engagement of said plate with the wall of said tubular support and without changing the shape of said plate 60 in portions other than said flange.

2. The combination with an electric lamp socket housed in a two piece casing including an open-ended cylindrical jacket and an inverted cap beneath said jacket and closely encompassing the lower end thereof,—of a 70 lamp receptive appliance designed to resemble a candle and mountable in said lamp socket in place of the lamp and having an outer, tubular wall extended downwardly as a skirt to encompass and conceal the upper portion of said jacket, and an attachment designed to resemble a candle holder and positioned to surround the entire length of said jacket between said cap and said appliance. 80

3. A device for securing an electric lamp receptacle shell to the wall of a surrounding tubular support, embodying in combination, a mounting plate fixedly secured in trans-axial relation to one end of said shell and extending outside the circumference of said shell to provide a mounting flange, the said mounting flange having a serrated edge and being channeled to provide for radial extension of said edge when flattened, thereby to effect mounting engagement of said plate with the wall of said tubular support and without changing the shape of said plate in portions other than said flange. 90

4. A device for securing an electric lamp receptacle shell to the wall of a surrounding tubular support, embodying in combination, a mounting plate fixedly secured in trans-axial relation to one end of said shell and extending outside the circumference of said shell to provide a mounting flange, the said mounting flange constituting three segmental portions each having a serrated edge and being channeled to provide for radial extension of said segmental portions when flattened, thereby to effect mounting engagement of said serrated edges with the wall of said tubular support and without changing the shape of said plate in portions other than said segmental flange portions. 100

5. An attachment for converting the appearance of an electric lamp socket and its casing having relatively large and small diameter portions, to make the same resemble a candle with its holder, embodying a tubular member fitted at one end to receive an electric lamp and at the other end to be received into said socket, a portion of said tubular member encompassing the small diameter portion of said casing, and a husk 115 member adapted to slide onto and encompass the large diameter portion of the lamp socket, said husk member axially overreaching said tubular member, whereby said socket with the exception of its said cap portion is substantially concealed by said attachment. 120

6. In an extension for lamp sockets, the combination with an exterior tube and an interior metal body assemblage, of means to 130

5 secure said assemblage to the interior of said tube and comprising two axially spaced metallic plates formed with alternate cut-out portions and channelled portions along its edge,—the cut-out portions in one plate aligning axially with the channelled portions in the other plate to permit insertion thereby of an axially acting tool from both ends of the tube to flatten said channelled 10 portions and project the edges of said plate into engagement with said tube.

15 7. In combination with a socket extension including a tubular casing of insulating material, an inner body structure comprising two screw shells pulled together by a conductive threaded tie bolt and nut insulated from said shells, said shells being spaced apart by a conductive spacer surrounding said tie bolt and electrically connecting the shells,—the said tie bolt being insulated from said spacer electrically connecting and retaining at each of its ends an electrical contact interior and substantially central of each screw shell.

20 25 8. In combination with a socket extension including a tubular casing of relatively soft material, an inner body structure to be mounted in said casing and comprising two screw shells pulled together by a conductive tie member and spaced apart by a conductive spacer surrounding said tie member and electrically connecting said screw shells,—the said tie member being insulated both from said screw shells and from said spacer 30 and providing at each of its ends a terminal electrical contact interior and substantially central of each of said screw shells,—together with holding disks of greater diameter than said screw shells providing means 35 of engagement with the walls of said casing.

40 45 9. An attachment for converting the appearance of an electric lamp socket having a cap and a casing, to resemble a candle with its holder, and comprising a tubular, candle-like member concealing the end of said socket casing opposite said cap, and a husk concealing the part of said socket casing adjacent said cap.

45 50 55 10. An attachment for converting the appearance of an electric lamp socket having a cap and a casing, to resemble a candle with its holder, and comprising a tubular, candle-like member concealing the end of said socket casing opposite said cap, and a husk belled out at its end adjacent said tubular member concealing the part of said socket casing adjacent said cap.

60 65 11. An attachment for converting the appearance of an electric lamp socket having a cap and a casing, to resemble a candle with its holder, and comprising a tubular, candle-like member concealing the end of said socket casing opposite said cap, and a husk belled out at its end adjacent said tubular member,

and concealing the part of said socket casing adjacent said cap;—said husk having a slot in its side to accommodate a switch key, pull chain guide, or other socket protuberance.

70

12. A fastening device for effecting the rigid assembly of an interior body structure and a surrounding casing therefor embodying a deformable plate receivable inside said casing with its edge closely adjacent the 75 interior wall of said casing, said plate having its central and peripheral portions disposed in a substantially common flat plane and having a portion intermediate said central and peripheral portions dented whereby 80 the flattening of said dented portion forces said plate edge into engagement with said casing in a plane of movement coincident with the said plane in which said central and peripheral plate portions were originally 85 disposed.

13. In combination with a lamp socket including a body portion carrying a lamp receptacle and enclosed by an open-ended, cylindrical shell, and a cap, telescopically overlapping and supporting said shell from below,—a fitting surrounding said shell and abutting against said cap and exposing a part of the latter so that said cap and said fitting resemble a unitary structure, said fitting flaring outwardly in its upper portion, and a candle-like socket-extension insertable in said lamp receptacle in place of the lamp, the end of said extension adjacent said lamp socket being surrounded by the outflaring 100 portion of said fitting.

14. The combination with an electric lamp socket comprising a round inner body portion carrying co-axially at one end thereof, a lamp receptacle of less diameter than said body portion, a shouldered cylindrical casing having an interior insulating sleeve and closely surrounding both said body portion and said receptacle and an outer mounting cap interlocking telescopically with the larger end of said casing whereby said body portion is retained between said cap and the shouldered portion of said casing; of an imitation candle fitting comprising a plug end insertable in said lamp receptacle in 110 place of the lamp and carrying at its opposite end another lamp receptacle, said fitting including a fixedly attached enclosing tube sufficiently large at said plug end to surround and conceal the smaller end of said 120 shouldered casing and positioned so to do, and a husk of proper diameter at its bottom end to sleeve over the larger end of said casing and to abut against said mounting cap, and flaring outwardly at its top end 125 to appear as a holder for said candle fitting.

In testimony whereof I have affixed my signature, this 25th day of January, 1923, at Boston, Massachusetts.

RAYMOND D. SMITH.
